DESIGN FOR A DOLL

Edna E. Brandenburg, New York, N. Y.

Application October 11, 1947, Serial No. 141,870

Term of patent 7 years

(Cl. D34—4)

To all whom it may concern:

Be it known that I, Edna E. Brandenburg, a citizen of the United States residing at New York, in the county and State of New York, have invented a new, original, and ornamental Design for Dolls, of which the following is a specification, reference being had to the accompanying drawing, forming part thereof.

I claim:

The ornamental design for a doll, as shown.

EDNA E. BRANDENBURG.
